J. NACHBAUR

VALVE

Filed Nov. 9, 1921

Josef Nachbaur, Inventor

John D. Schillie per
Attorney

UNITED STATES PATENT OFFICE.

JOSEF NACHBAUR, OF ARBON, SWITZERLAND.

VALVE.

Application filed November 9, 1921. Serial No. 513,964.

To all whom it may concern:

Be it known that I, JOSEF NACHBAUR, a citizen of Germany, residing at Arbon, Switzerland, have invented certain new and useful Improvements in Valves, of which the following is a specification.

The present invention has reference to certain new and useful improvements in valves, and relates more particularly to automatically periodically actuatable valves, such as are used for instance for flushing out ground water, sewerage, or the like, and the invention specifically resides in the construction, arrangement and cooperation of parts, as hereinafter described and claimed.

My invention will best be understood when described in connection with the accompanying drawing, in which Fig. 1 is a longitudinal vertical section through the valve parts proper, partly in elevation: Fig. 2 is a plan view thereof, and Fig. 3 illustrates the valve in connection with a water tank.

25 The valve casing 1 is interposed in a pressure water conduit 2, which leads into a collector or tank 3, which latter includes an injector 4 and a discharge standpipe 5. The valve proper is of well known construction, comprising a valve seat and a valve cooperating therewith under the influence of a lever 6 articulated to the valve casing and acted on by a float 7 depending from the outer free end of lever 6 into

35 the tank, as clearly shown in Fig. 3.

According to the present invention the valve 8 is provided with an extension 8' projecting outwardly through a bore in the valve casing 1, and this extension is provided with a vertical perforation 9 in which engages the upper, substantially vertically directed arm 10 of a bell crank, fulcrumed on the cross-pin 11, and to whose other, substantially horizontally directed arm 12 40 is pivoted at 12' the end of a rod 13, an adjusting disk 14 threading on this threaded rod portion, and the parts forming a kind of knuckle-joint, as it were. The other reduced rod end supports a

50 dished disk 15 and freely passes through a bridge member 16 fixed to the two side cheeks 17, 17' respectively forming the valve actuating lever 6. The inner end of this latter is rockably journaled on the cross-pin 11. A coil spring 18 is interposed be-

tween the two disks 14 and 15 about the rod 13 and its tension is readily adjusted by respective manipulation of the disk 14.

The operation of the device is as follows: Normally, that is, to say when the tank 3 is practically empty and the float 7 is in its lowermost relative position, the valve 8 is pressed firmly onto its seat, so that no pressure water can pass through the conduit 2 to start the injector 4. Upon ground water, sewerage, or the like rising in the tank, the float 7 will correspondingly be lifted and then cause the lever 6 to swing upwardly about 11 with the rod 13 following this movement and the slowly tensioning spring 18 influencing the bell crank in such manner that its upper arm 10 forces the valve with increasing pressure onto its seat. Upon the float continuing its upward movement, the lever 6 with rod 13 will correspondingly swing further upwardly until there comes a moment when the longitudinal axes of the rod and the horizontal bell crank arm form a straight line, or in other words a straight line passes axially through the rod 13 and the centers of the fulcrums 12' and 11. Immediately after, the spring 18, which was gradually compressed, though only to a relatively small degree, suddenly extends and causes the bell crank to rock back about 11, bending through in a downward direction the knuckle joint at 12', with the result that the bell crank arm 10 now moves the valve away from its seat, which allows pressure water to pass through into the conduit 2 to operate the injector for ejecting the water accumulation in the tank 3 out through discharge pipe 5. The receding water level causes the float to follow, with the result that the parts again assume their initial position, after the knuckle joint at 12' has bent through again upwardly, causing the spring 18 to act again for closing the valve, which stops the operation of the injector.

By manipulating the disk 14, the helical spring can be properly tensioned to control different water pressures obtaining in the valve.

What I claim is:—

1. In a device of the character set forth, in combination with a pressure conduit, a valve casing and a float-controlled valve therein for controlling said pressure conduit, means for periodically operating said

105

110

valve, comprising a lever, a float acting on the one end of said lever and the other end thereof pivoted to said valve casing, a bell crank pivoted to said valve casing coaxially with said lever, and the one arm of said bell crank adapted to operate said valve, a rod linked at one end to the other arm of said bell crank and guided at its other end in said lever, spring means interposed between said float-influenced lever and said bell crank and urgently acting on said valve substantially in the direction of valve displacement, and means for adjusting the tension of said spring means to the degree of pressure obtaining in said pressure conduit.

2. In a device of the character set forth, in combination with a pressure conduit and

a valve controlling said conduit, a float-controlled lever, comprising two parallel cheeks 20 and a bridge member connecting the outer ends of said cheeks and their other ends pivotally secured to the casing of said valve, a bell crank also pivotally secured to the valve casing coaxially with the suspension 25 of said float-controlled lever, the substantially vertically extending bell crank arm adapted to actuate said valve, a rod positioned between said two lever cheeks, its outer free end guided in said bridge member and its inner end pivotally secured to the substantially horizontally extending bell crank arm, a helical spring surrounding said rod, and means for regulating the tension of said spring.

JOSEF NACHBAUR.
